G. SKAGLIN.
SWITCH LOCK.
APPLICATION FILED OCT. 13, 1915.

1,200,895.

Patented Oct. 10, 1916.

UNITED STATES PATENT OFFICE.

GEORGE SKAGLIN, OF TUSTIN, MICHIGAN.

SWITCH-LOCK.

1,200,895.

Specification of Letters Patent. Patented Oct. 10, 1916.

Application filed October 13, 1915. Serial No. 55,727.

To all whom it may concern:

Be it known that I, GEORGE SKAGLIN, a citizen of the United States, residing at Tustin, in the county of Osceola, State of Michigan, have invented certain new and useful Improvements in Switch-Locks; and I do hereby declare the following to be a full, clear, and exact description of the invention, such as will enable others skilled in the art to which it appertains to make and use the same.

This invention relates to switch locks and is particularly adapted for use in connection with the switch of an automobile ignition circuit.

The object of the invention is to provide a lock of the character named embodying an improved construction, and which will be simple, efficient and comparatively inexpensive to manufacture.

With the above and other objects in view the invention consists in the details of construction and in the arrangement and combination of parts to be hereinafter more fully described and particularly pointed out in the appended claims.

In describing the invention in detail reference will be had to the accompanying drawings wherein like characters of reference denote corresponding parts in the several views, and in which—

Figure 1 is a front view of a lock constructed in accordance with the invention; Fig. 2, a view similar to Fig. 1 with the front side of the casing removed and the parts in the position they would occupy when the switch is closed; Fig. 3, a view similar to Fig. 2 with the parts in the position they would occupy when the switch is locked opened; Fig. 4, a top view of the lock with the top of the casing removed; Fig. 5, a view similar to Fig. 4 with the parts in the position shown in Fig. 3; Fig. 6, a section on the line 6—6 of Fig. 3, and Fig. 7, a section on the line 7—7 of Fig. 3.

Referring to the drawings the invention is shown as comprising a casing A including a rear wall 10 and a front wall 11. Mounted on the rear wall 10 is a frame 12 which supports terminals 13 and 14 adapted to be connected in the ignition circuit of an automobile. Pivoted to the terminal 14 is a knife 15 which can be moved into and out of engagement with the terminal 13 as will be obvious. These terminals 13 and 14 and the knife 15 of course constitute the switch

of the ignition circuit. Rotatably mounted in the walls 10 and 11 is a plurality of shafts 16, 17 and 18 and fixed upon these shafts within the casing A are disks 19, 20 and 21 respectively. Formed in the rear wall 10 is a triangular opening 22 in which is slidably mounted the triangular enlargement 23 of a bar 24 which latter is also slidably mounted in the wall 11 and is pivotally connected to the knife 15 so that by sliding said bar the knife 15 can be moved into and out of engagement with the terminal 13. The disks 19, 20 and 21 are provided respectively with notches 25 which in certain positions of said disk register with a portion of the openings 22.

Pivoted upon the wall 10 is a locking lever 26 which is normally urged to locking position by a spring 27. The lever 26 is provided with a notch 28 while the disk 20 carries a projection 29 adapted to engage the lever when the disk 20 is rotated in one direction and lift said lever out of locking position. Opposite rotation of the disk 20 will cause the projection 29 to engage in the notch 28 and then pass under the lever 26 so as not to interfere with the rotation of the disk in that direction. When the disks are positioned as shown in Fig. 2 the notches 25 will register with portions of the opening 22 so that the bar 24 can be moved longitudinally to engage and disengage the knife 15 with and from the terminal 13. It will be noted however that when the knife 15 is disengaged from the terminal 13 the enlargement 23 will move out of the opening 22 and the locking lever 26 will move behind the enlargement 23 and thus lock the knife 15 out of engagement with the terminal 13 and maintain the ignition circuit broken. After this condition arises the disks 19, 20 and 21 are rotated so as to dispose the notches 25 out of registration with the opening 22 when the locking of the switch in open position is complete. To release the lock disks 19 and 21 are rotated to dispose the notches 25 in the position shown in Fig. 2 and the disk 20 is rotated to the left to raise the lever 26 out of locking position and dispose the notch 25 thereof in registration with the opening 22 when the knife 15 can be moved to close the ignition circuit associated. Mounted on each shaft 16, 17 and 18 adjacent the outer face of the wall 11 is a pointer 30 and arranged around each of said shafts on the outer face of the wall 11 is a dial 31. By

this means the lock can be readily set to a desired combination and operated with convenience by utilizing the relation between respective pointers 30 and the associated dial.

5 What is claimed is:—

1. In a device of the class described the combination of a casing, a frame mounted on the casing, circuit terminals carried by the frame, a switch knife pivoted to one terminal and moved into and out of engagement with the other terminal, a plurality of shafts rotatably mounted in opposite walls of the casing, a bar slidably mounted in opposite walls of the casing and connected to said knife whereby the sliding of the bar will move the knife into and out of engagement with one of the circuit terminals, an enlargement on said bar adapted to move in an opening in the wall of the casing adjacent the frame, a disk mounted on each of said shafts within the casing and provided with a notch adapted to register with the opening in one position of said disk to permit sliding of the bar, and said disk being movable behind the enlargement on the bar when the knife is out of engagement with the circuit terminal whereby the bar is locked against movement in a direction to engage the knife with the circuit terminal.

2. In a device of the class described, the combination of a casing, a frame mounted on said casing, an electric switch carried by the frame a bar slidably mounted in the casing and connected to the switch to open and close the latter, an enlargement on said bar adapted for movement in an opening in the wall of the casing, a shaft rotatably mounted in the casing, a disk fixed on said shaft and provided with a notch adapted to register with the opening in one position to 30 permit sliding movement of the bar, and said disk being adapted to be moved behind the enlargement when the switch is opened to 35 lock the bar against movement to close the switch, a locking lever mounted in the casing, spring means constantly tending to move the lever toward the bar whereby said lever will pass behind the enlargement when the switch is opened, and means on the disk engageable with the lever to move the latter 40 to released position when said disk is rotated in one direction.
